UNITED STATES PATENT OFFICE.

JAMES CALVIN, OF CLEVELAND, OHIO, ASSIGNOR OF ONE-HALF TO WILLIAM J. BAILEY,
OF CLEVELAND, OHIO.

DESIGN FOR A HELP-SELF COUNTER.

54,239.

Specification for Design.

Patented Dec. 9, 1919.

Application filed July 21, 1919. Serial No. 312,456. Term of patent 7 years.

To all whom it may concern:

Be it known that I, JAMES CALVIN, a citizen of the United States, residing at Cleveland, in the county of Cuyahoga and State of Ohio, have invented a new, original, and ornamental Design for a Help-Self Counter, of which the following is a specification, reference being had to the accompanying drawings, forming a part thereof.

In said drawing, Figure 1 is a perspective view; Fig. 2 is an end elevation; Fig. 3 is a sectional elevation.

I claim:

The design for a help-self counter substantially as herein shown.

JAMES CALVIN.
